Wyomissing Corporation, Reading, Pa., a corpora-
tion of Pennsylvania

Filed May 29, 1968, Ser. No. 12,123

Term of patent 14 years

Int. Cl. D5—99

U.S. Cl. D3—32

FIG. 1.

FIG. 2.

FIG. 3.

FIG. 4.

FIG. 1 is a perspective view showing both sides of an elastic band embodying my new design, illustrating in full lines the salient feature thereof;

FIG. 2 is an enlarged fragmentary face view of the anchor elastic shown in FIG. 1;

FIG. 3 is an enlarged longitudinal sectional view taken on the line 3—3 of FIG. 2; and

FIG. 4 is an enlarged transverse sectional view taken on the irregular section line 4—4 of FIG. 2.

The salient feature consists of a plurality of laterally spaced rubber-like solid beads extending along the length of one surface of the band and having a series of indentations therein:

I claim:

The ornamental design for an elastic band, substantially as shown and described.
